UNITED STATES PATENT OFFICE.

WILLIAM HORN, OF ONEONTA, NEW YORK, ASSIGNOR TO QUALITY SILK MILLS, INC.,
OF NEW YORK, N. Y., A CORPORATION OF NEW YORK.

DESIGN FOR ORNAMENTATION FOR A GLOVE OR SIMILAR ARTICLE.

59,477.

Specification for Design.

Patented Oct. 25, 1921.

Application filed December 31, 1920. Serial No. 434,378. Term of patent 3½ years.

To all whom it may concern:

Be it known that I, WILLIAM HORN, a citizen of the United States, and a resident of Oneonta, county of Otsego, and State of New York, have invented a new, original, and ornamental Design for Ornamentation for a Glove or Similar Article, of which the following is a specification, reference be-

ing had to the accompanying drawing, which illustrates a plan view of the design applied to a portion of a glove.

I claim—

The ornamental design for ornamentation for a glove or similar article, as shown.

WILLIAM HORN.
